3 Sheets-Sheet 1

<img alt="A detailed technical line drawing of a mechanical assembly, likely a lock mechanism, labeled Fig. 41. The drawing shows a rectangular housing with various internal parts labeled with numbers. Key components include a central locking mechanism with a pin tumbler assembly (labeled 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 299, 300, 301, 302, 303, 304, 305, 306, 307, 308, 309, 309, 310, 311, 312, 313, 314, 315, 316, 317, 318, 319, 319, 320, 321, 322, 323, 324, 325, 326, 327, 328, 329, 329, 330, 331, 332, 333, 334, 335, 336, 337, 338, 339, 339, 340, 341, 342, 343, 344, 345, 346, 347, 348, 349, 349, 350, 351, 352, 353, 354, 355, 356, 357, 358, 359, 359, 360, 361, 362, 363, 364, 365, 366, 367, 368, 369, 369, 370, 371, 372, 373, 374, 375, 376, 377, 378, 379, 379, 380, 381, 382, 383, 384, 385, 386, 387, 388, 389, 389, 390, 391, 392, 393, 394, 395, 396, 397, 398, 399, 399, 400, 401, 402, 403, 404, 405, 406, 407, 408, 409, 409, 410, 411, 412, 413, 414, 415, 416, 417, 418, 419, 419, 420, 421, 422, 423, 424, 425, 426, 427, 428, 429, 429, 430, 431, 432, 433, 434, 435, 436, 437, 438, 439, 439, 440, 441, 442, 443, 444, 445, 446, 447, 448, 449, 449, 450, 451, 452, 453, 454, 455, 456, 457, 458, 459, 459, 460, 461, 462, 463, 464, 465, 466, 467, 468, 469, 469, 470, 471, 472, 473, 510, 511, 512, 513, 514, 515, 516, 517, 518, 519, 519, 520, 521, 522, 523, 524, 525, 526, 527, 528, 529, 529, 530, 531, 532, 533, 534, 535, 536, 537, 538, 539, 539, 540, 541, 542, 543, 544, 545, 546, 547, 548, 549, 549, 550, 551, 552, 553, 554, 555, 556, 557, 558, 559, 559, 560, 561, 562, 563, 564, 565, 566, 567, 568, 569, 569, 570, 571, 572, 573, 574, 575, 576, 577, 578, 579, 579, 580, 581, 582, 583, 584, 585, 586, 587, 588, 589, 589, 590, 591, 592, 593, 594, 595, 596, 597, 598, 599, 599, 600, 601, 602, 603, 604, 605, 606, 607, 608, 609, 609, 610, 611, 612, 613, 614, 615, 616, 617, 618, 619, 619, 620, 621, 622, 623, 624, 625, 626, 627, 628, 629, 629, 630, 631, 632, 633, 634, 635, 636, 637, 638, 639, 639, 640, 641, 642, 643, 644, 645, 646, 647, 648, 649, 649, 650, 651, 652, 653, 654, 655, 656, 657, 658, 659, 659, 660, 661, 662, 663, 664, 665, 666, 667, 668, 669, 669, 670, 671, 672, 673, 674, 675, 676, 677, 678, 679, 679, 680, 681, 682, 683, 684, 685, 686, 687, 688, 689, 689, 690, 691, 692, 693, 694, 695, 696, 697, 698, 699, 699, 700, 701, 702, 703, 704, 705, 706, 707, 708, 709, 709, 710, 711, 712, 713, 714, 715, 716, 717, 718, 719, 719, 720, 721, 722, 723, 724, 725, 726, 727, 728, 729, 729, 730, 731, 732, 733, 734, 735, 736, 737, 738, 739, 739, 740, 741, 742, 743, 744, 745, 746, 747, 748, 749, 749, 750, 751, 752, 753, 754, 755, 756, 757, 758, 759, 759, 760, 761, 762, 763, 764, 765, 766, 767, 768, 769, 769, 770, 771, 772, 773, 774, 775, 776, 777, 778, 779, 779, 780, 781, 782, 783, 784, 785, 786, 787, 788, 789, 789, 790, 791, 792, 793, 794, 795, 796, 797, 798, 799, 799, 800, 801, 802, 803, 804, 805, 806, 807, 808, 809, 809, 810, 811, 812, 813, 814, 815, 816, 817, 818, 819, 819, 820, 821, 822, 823, 824, 825, 826, 827, 828, 829, 829, 830, 831, 832, 833, 834, 835, 836, 837, 838, 839, 839, 840, 841, 842, 843, 844, 845, 846, 847, 848, 849, 849, 850, 851, 852, 853, 854, 855, 856, 857, 858, 859, 859, 860, 861, 862, 863, 864, 865, 866, 867, 868, 869, 869, 870, 871, 872, 873, 874, 875, 876, 877, 878, 879, 879, 880, 881, 882, 883, 884, 885, 886, 887, 888, 889, 889, 890, 891, 892, 893, 894, 895, 896, 897, 898, 899, 899, 900, 901, 902, 903, 904, 905, 906, 907, 908, 909, 909, 910, 911, 912, 913, 914, 915, 916, 917, 918, 919, 919, 920, 921, 922, 923, 924, 925, 926, 927, 928, 929, 929, 930, 931, 932, 933, 934, 935, 936, 937, 938, 939, 939, 940, 941, 942, 943, 944, 945, 946, 947, 948, 949, 949, 950, 951, 952, 953, 954, 955, 956, 957, 958, 959, 959, 960, 961, 962, 963, 964, 965, 966, 967, 968, 969, 969, 970, 971, 972, 973, 974, 975, 976, 977, 978, 979, 979, 980, 981, 982, 983, 984, 985, 986, 987, 988, 989, 989, 990, 991, 992, 993, 994, 995, 996, 997, 998, 999, 999, 1000, 1001, 1002, 1003, 1004, 1005, 1006, 1007, 1008, 1009, 1009, 1010, 1011, 1012, 1013, 1014, 1015, 1016, 1017, 1018, 1019, 1019, 1020, 1021, 1022, 1023, 1024, 1025, 1026, 1027, 1028, 1029, 1029, 1030, 1031, 1032, 1033, 1034, 1035, 1036, 1037, 1038, 1039, 1039, 1040, 1041, 1042, 1043, 1044, 1045, 1046, 1047, 1048, 1049, 1049, 1050, 1051, 1052, 1053, 1054, 1055, 1056, 1057, 1058, 1059, 1059, 1060, 1061, 1062, 1063, 1064, 1065, 1066, 1067, 1068, 1069, 1069, 1070, 1071, 1072, 1073, 1074, 1075, 1076, 1077, 1078, 1079, 1079, 1080, 1081, 1082, 1083, 1084, 1085, 1086, 1087, 1088, 1089, 1089, 1090, 1091, 1092, 1093, 1094, 1095, 1096, 1097, 1098, 1099, 1099, 1100, 1101, 1102, 1103, 1104, 1105, 1106, 1107, 1108, 1109, 1109, 1110, 1111, 1112, 1113, 1114, 1115, 1116, 1117, 1118, 1119, 1119, 1120, 1121, 1122, 1123, 1124, 1125, 1126, 1127, 1128, 1129, 1129, 1130, 1131, 1132, 1133, 1134, 1135, 1136, 1137, 1138, 1139, 1139, 1140, 1141, 1142, 1143, 1144, 1145, 1146, 1147, 1148, 1149, 1149, 1150, 1151, 1152, 1153, 1154, 1155, 1156, 1157, 1158, 1159, 1159, 1160, 1161, 1162, 1163, 1164, 1165, 1166, 1167, 1168, 1169, 1169, 1170, 1171, 1172, 1173, 1174, 1175, 1176, 1177, 1178, 1179, 1179, 1180, 1181, 1182, 1183, 1184, 1185, 1186, 1187, 1188, 1189, 1189, 1190, 1191, 1192, 1193, 1194, 1195, 1196, 1197, 1198, 1199, 1199, 1200, 1201, 1202, 1203, 1204, 1205, 1206, 1207, 1208, 1209, 1209, 1210, 1211, 1212, 1213, 1214, 1215, 1216, 1217, 1218, 1219, 1219, 1220, 1221, 1222, 1223, 1224, 1225, 1226, 1227, 1228, 1229, 1229, 1230, 1231, 1232, 1233, 1234, 1235, 1236, 1237, 1238, 1239, 1239, 1240, 1241, 1242, 1243, 1244, 1245, 1246, 1247, 1248, 1249, 1249, 1250, 1251, 1252, 1253, 1254, 1255, 1256, 1257, 1258, 1259, 1259, 1260, 1261, 1262, 1263, 1264, 1265, 1266, 1267, 1268, 1269, 1269, 1270, 1271, 1272, 1273, 1274, 1275, 1276, 1277, 1278, 1279, 1279, 1280, 1281, 1282, 1283, 1284, 1285, 1286, 1287, 1288, 1289, 1289, 1290, 1291, 1292, 1293, 1294, 1295, 1296, 1297, 1298, 1299, 1299, 1300, 1301, 1302, 1303, 1304, 1305, 1306, 1307, 1308, 1309, 1309, 1310, 1311, 1312, 1313, 1314, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, 1911, 1912, 1913, 1914, 1915, 1916, 1917, 1918, 1919, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1959, 1959, 1960, 1961, 1962, 1963, 1964, 1965, 1966, 1967, 1968, 1969, 1969, 1970, 1971, 1972, 1973, 1974, 1975, CONTROL

George Knaak, Milwaukee, Wis.

Application July 16, 1942, Serial No. 451,101

16 Claims. (CL 200—81.5)

This invention relates to a control device for regulating the operation of a refrigerating system, and more particularly to a thermostatically controlled electric switch mechanism for controlling the starting and stopping of the electric motor employed in such a system to drive the compressor thereof.

One of the objects of the present invention is to provide a control device of this character which facilitates the making of operating temperature changes frequently and easily.

Broadly speaking, this object of the invention is accomplished by combining with the operating mechanism of the switch two sets of bellows, lever, and spring mechanisms, both controlled by the pressure on the low or evaporating side of the refrigerating system, but independently adjustable so that a difference between start and stop can be adjusted to cover the entire range.

Another and important object of the invention is to prevent starting of the system under adverse condensing pressures. By preventing starting against excessive head pressures, a large factor in the cause of motor trouble is eliminated.

This latter object is accomplished in general by organizing with the control a third bellows subject to the control of the pressure on the condensing or high pressure side of the refrigerating system and exercising a dominant or master control in the device when the head pressure is excessive. When the high pressure bellows is energized by virtue of the existence of excessive head pressure, operation of the equipment cannot be resumed until this head pressure recedes to a predetermined degree, a degree selected, of course, with regard to the capacity of the motor.

Another object of the invention is to provide a controlling device of this character and having the advantages and capacities and which is simple and durable as well as compact in construction, reliable and efficient in operation and easy and comparatively inexpensive to manufacture and maintain.

Other objects and advantages reside in certain novel features of the construction, arrangement, and combination of parts, which will be hereinafter more fully described and particularly pointed out in the appended claims, reference being had to the accompanying drawings forming a part of this specification, and in which:

Figure 1 is a view in side elevation of a control device embodying the present invention, the cover plate of the housing of the device being removed for the sake of illustration and the switch being shown in open position under the

control of the cut-out bellows responsive to low side regulation;

Figure 2 is a view similar to Figure 1 but illustrating the switch in closed position under the control of the cut-in bellows responsive to low side regulation;

Figure 3 is a fragmentary view similar to Figures 1 and 2 but illustrating the switch opened by the high condensing pressure bellows;

10 Figure 4 is a view in horizontal cross section taken on line 4—4 of Figure 2 and looking in the direction of the arrows;

Figure 5 is a view in transverse vertical cross section taken on line 5—5 of Figure 2 and looking in the direction of the arrows;

15 Figure 6 is a view in longitudinal vertical cross section taken on line 6—6 of Figure 4 and looking in the direction of the arrows;

Figure 7 is a detail view in top plan illustrating the bellows-actuated levers employed to open and close the switch in response to low side regulation;

Figure 8 is a view thereof in side elevation;

15 Figure 9 is a detail view in front elevation of the lever employed for controlling the switch from the high pressure side of the system;

Figure 10 is a view in side elevation of the lever illustrated in Figure 9;

20 Figure 11 is a detailed view in front elevation of the electric switch employed for controlling the operation of the motor;

Figure 12 is a view thereof in end elevation;

Figure 13 is a detail view in top plan of the housing for the cut-in and cut-out bellows;

25 Figure 14 is a view thereof in longitudinal vertical cross section taken on line 14—14 of Figure 13;

Figure 15 is a fragmentary detail view in top plan showing the manually adjustable knob for the cut-out thermostat spring; and

30 Figure 16 is a view in vertical cross section taken on line 16—16 of Figure 15.

Referring to the drawings, and more particularly to Figures 1 to 6, inclusive, it will be seen that a control device embodying the present invention includes a suitable housing, designated generally at 1, and preferably constructed of sheet metal. The housing is in the form of a rectangular box-like structure, and preferably has a removable cover 2.

Within the housing 1 is an electric switch, designated as a whole at S. The switch S is constituted to provide a single pole, single throw switch wherein snap action is provided by means of a permanent magnet. To this end the switch

S comprises a panel 3 of insulating material, which is carried by a sheet metal bracket 4 fastened by screw 5 to one of the walls of the housing. A fixed switch contact 6 is mounted on the insulating panel 3 and may be carried by a portion of a binding post 7 equipped with a binding screw 8 to facilitate the attachment of a lead or wire (not shown) thereto. The fixed contact 6 is connected to one side of the electric motor (not shown) but usually employed to drive the compressor of a refrigerating machine. Operable with the fixed contact 6 is a movable contact button 9. This contact button 9 may be riveted or otherwise suitably attached to a blade spring 10 (see Figures 11 and 12) which is in turn fastened at one end to a pivoted contact carrier 11. The contact carrier 11 is provided with a circular opening through which the contact button 9 is projected under the influence of the inherent elasticity or bias of the blade spring 10. The lower end of the contact carrier 11 is fixed to and carried by a rocker arm 12 preferably of insulating material such as suitable laminated plastic composition. The hub of this rocker arm is pivotally supported on a pivot bolt 13. The bolt 13 extends through and is supported on a bearing opening provided therefor in an extension 3' of the insulating panel 3 and the parts are held assembled by a nut 14 threaded on the bolt and coacting with the insulating panel. A flexible wire 15 is provided and is connected at one end, as at 16, to the contact carrier 11. The opposite end of this wire 15 is connected to a binding post 17 fastened to the insulating panel by a screw 18 and equipped with a binding screw 19 to facilitate its connection to the opposite side of the motor circuit from that to which the binding post 7 is connected. A retractile coil spring 20 has one end attached to the contact carrier 11 and has its opposite end fixed to the panel 3, the spring 20 being tensioned to bias the switch S to closed position.

Combined with the fixed contact 6 of the switch S is a permanent magnet 21, the magnet 21 being shown U-shaped or of horse-shoe form, and having its legs straddling the fixed contact 6. The magnetic field of the magnet 21 so influences the contact carrier 11, and the movable contact 9, as to cause the switch S to open and close with a snap action, thereby minimizing arcing.

The opening and closing of the switch S is under the control of three bellows, designated generally at B₁, B₂, and B₃. The bellows B₁ and B₂ are in turn controlled by the pressure on the low or evaporating side of the refrigerating system. The bellows B₃ is subject to the control of the pressure on the condensing or high pressure side of the refrigerating system.

The controlling action of these bellows B₁, B₂, and B₃ is exerted on the switch S through a special system of lever and springs, which will be hereinafter fully described.

The bellows B₁ and B₂ are carried by a bellows housing, designated generally at 22. The bellows housing 22 may be constituted of metal of suitably heavy cross section and is made up of two cup-like members 23 and 24, one receiving and housing the bellows B₁ and the other receiving and housing the bellows B₂. The interior of the cup-like members are in open communication due to the provision of an opening or passage 26 in the web which separates them. Consequently, both the bellows B₁ and B₂ are subjected to the same pressure.

A fitting 25 is connected to the cup-like member 24 to facilitate its connection with a suitable thermostat or temperature element, such as the familiar capillary tube and bulb, with the bulb in clamped contact with the evaporating coil. This, or any other similar suitable conventional thermostatic control arrangement, will result in the bellows B₁ and B₂ being subjected to a pressure which varies directly as the pressure or temperature in the evaporating coil or low pressure side of the refrigerating system.

The bellows housing 22 is preferably positioned below the bottom of the main housing 1 and is fastened thereto by screws 22' which also serve to secure supporting feet 27 to the one side of the bellows housing 22.

The bellows B₁ and B₂ are operatively interrelated with the operating mechanism for the switch S through a novel and special system of lever mechanism which will presently be described.

This special type of lever mechanism is so combined with the bellows and with the operating mechanism for the switch S that the bellows B₁ functions as a cut-out control in that when it exerts a controlling function on the switch S, it serves to shift the same to open position. The bellows B₂ on the other hand is so combined with the operating mechanism for the switch S that when it exerts a controlling function thereover, it serves as a cut-in control, that is it functions to shift the switch S to closed position.

The device, with only its bellows B₁ and B₂, and with the special type of lever and spring mechanism operatively interrelating with the switch S, is possessed of a capacity to exercise a very useful and advantageous purpose. Its function is enhanced by organizing therewith the bellows B₃ responsive to the control of the pressure on the condensing or high pressure side of the refrigerating system, but it is to be understood, as just indicated, that the bellows B₁ and B₂, through the control that they exercise, have advantage and utility of themselves.

The lever and spring mechanism operatively interrelating the bellows B₁ and B₂, with the operating mechanism for the switch S, will now be described.

The pointed or driving projections 28 and 28' of the bellows B₁ and B₂ extend up through openings provided therefor in the bottom wall of the main housing 1. Supported on the floor of the housing 1 and immediately over the bellows B₁ and B₂ is a bracket 30 constructed of a sheet metal stamping of suitable gauge and serving to support transversely extending fulcrum pins 31 and 32. These fulcrum pins have the cross section shown in Figure 6 so as to present downwardly facing knife edges designed to engage suitable cooperative formations on the upper surfaces of intermediate portions of the bellows levers 33 and 34 (see Figure 6). The under surfaces of these levers 33 and 34 at points spaced lengthwise thereof from the fulcrum pins 31 and 32, have socketed formations which are in cooperative engagement with the pointed projections 28 and 28' of the bellows B₁ and B₂ (see Figures 5 and 6).

Opposing the action of the bellows B₁ and B₂ on the levers 33 and 34 are coil springs 35 and 36, the spring 35 being connected to the bellows lever 33 and the spring 36 to the bellows lever 34. The tension of the springs 35 and 36 is independently variable or adjustable to determine the

range of operation of the control. The structure by which the tension of springs 35 and 36 is varied or adjusted will be hereinafter more fully described.

By having the cut-in and cut-out adjustments independent one from the other, a difference between start and stop can be adjusted to cover the entire range. Furthermore, since the adjustments may be made on an outside of the casing, operating temperature changes may be frequently and easily made.

The manner in which the levers 33 and 34 are operatively interconnected with the switch S will now be described.

The bellows lever 33 is provided with an arm or portion 37 which is cooperable with the inner end of a pin 38 carried by one arm of the rocker 12, so that when the lever 33 is rotated in a counter-clockwise direction, as viewed in Figure 1, its portion 37 presses upwardly on the inner end of the pin 38 to swing the rocker 12 in a clockwise direction and consequently cause the contact carrier 11 to correspondingly rotate, thereby opening the switch or bring it to the position shown in Figure 1. When this action occurs, the pressure in the low side of the system has been reduced so that the spring 35 overcomes the action of the bellows B₁. As the evaporating coil of the refrigerating system warms up, the pressure in the coil rises. This effects a corresponding increase in the pressure in the bellows B₁ and eventually the pressure therein reaches the point where it overcomes the action of the spring 35 so as to so move the lever 33 to the position shown in Figure 2, in which position the lever 33 will free the switch S and permit of its closure.

The closing of the switch S, when the head or condensing pressure in the system is not excessive, is under the control of the cut-in bellows B₂ and its lever and spring mechanism.

The bellows lever 34 of the bellows B₂ has an upstanding lug 40 integral with its outer side edge and carrying an outwardly projection fixed pivot stud 41. A switch control lever, designated generally at 42, is pivotally supported on the pivot stud 41. The switch control lever 42 has its body portion constituted of sheet metal stamping of angular formation in transverse vertical cross section. The vertical flange of the body portion of the lever 42 has a bearing sleeve 43 fixed to and projecting from an opening provided therein. The pivot stud 41 extends through its bearing sleeve. A cotter pin 44 prevents endwise displacement of the sleeve or of the stud. A spring finger 45 has one end riveted or otherwise suitably secured to the horizontal flange of the body portion of the switch lever 42, and its other end projects beyond the horizontal flange of the body portion of the lever and bears against a pin 46 carried by the adjacent arm of the rocker of the switch S. The vertical flange of the body portion of the switch lever has a rearward projection 47 which overlies and is adapted to have engagement with a short vertical pin 48 carried by a lateral extension 49 to the bellows lever 34. The extension 47 and pin 48 provide a driving connection between the bellows lever 34 and the switch control lever 42, and yet the switch control lever 42 may be rotated with respect to the bellows lever 34 in one direction for a purpose which will hereinafter more clearly appear. The spring finger 45, while resilient, is sufficiently stiff to hold the switch S open after the switch has been moved to open position by the cut-out bel-

lows B₁ and its lever and spring mechanism, since the spring finger is stiffer than the switch spring 20. The spring finger is not, however, sufficiently stiff to overcome the combined force of the switch spring 20 and the permanent magnet 21 when the switch S is in closed position and the contact carrier 11 and movable contact 9 are in the field of the magnet 21.

The bellows B₂ is hence effective to control the closing of the switch S when the head or condensing pressure in the system is not excessive. It cannot, however, function to open the switch S since the control, which the bellows B₂ exerts over switch S, is exerted through the spring finger 45, which, as previously described, is not sufficiently stiff to overcome the combined force of the switch spring 20 and the permanent magnet 21. And during the phase of the operation that the bellows B₂ is controlling the closing of the switch S, the spring finger 45 flexes to provide for the desired lag.

The high pressure bellows B₃ is enclosed in a bellows housing 50 suitably fastened to one of the end walls of the main housing 1. The bellows housing 50 is provided with a fitting 51 to facilitate its connection with suitable thermostat or temperature element, such as the familiar capillary tube and bulb, with the bulb in clamped contact with the condensing or high pressure side of the refrigerating system, so that the pressure to which the bellows B₃ is subject varies directly as the pressure of the condensing or high pressure side of the system. In many instances the pressure of the refrigerant in the evaporating coil is utilized as the controlling medium rather than the temperature. The bellows B₃ is equipped with the usual pointed or driving projection 52 which projects through an opening provided therefor in the adjacent end wall of the housing 1 and also through an opening provided in a switch supporting bracket, designated generally at 53 and suitably fixed to the inside of the end wall of the main housing 1 adjacent the bellows B₃. A lever, designated generally at 54, is supported for rocking movement on a pivot bolt 55 supported in suitable bearing lugs 56 which may be integrally formed with the bracket 53. The lever 54 may be advantageously constituted of a sheet metal stamping, and has a plate-like arm 57 formed with a depression or socket formation 58 adapted to have suitable driving contact with the driving projection 52 of the bellows B₃. Integral with and projecting angularly from the plate-like arm 57 are two lever arms, designated at 59 and 60, respectively. The lever arm 59 is connected to the lower end of a retractile coil spring 61, the upper end of which is adjustably supported on the top wall of the main housing 1. The spring 61 opposes the action of the bellows B₃. The arm 60 of the lever 54 is provided with a laterally projecting pin or roller 62 which overlies the vertical flange of the switch lever 42. When excessive condensing pressures exist, the pressure on the bellows B₃ is correspondingly increased and the projection 52 of the bellows B₃ rocks the lever 54 in a counter-clockwise direction, as viewed in Figures 1, 2, 3, and 6. This swings the lever arm 60 and its roller or pin 62 down to the position shown in Figure 3, in which position the roller 62 wipes against the upper edge of the vertical flange of the switch control lever 42, thereby rocking this lever 40 in a counter-clockwise direction and causing its forward projection 40' to bear downwardly on the pin 46 so as to rock the rocker 12 and open the switch S.

As long as the excessive condensing pressures obtain, the switch S will remain open and this independently of the action of the bellows B₁ and B₂. When the bellows B₃ functions in the manner described under the influence of the excessive condensing pressures, it becomes the dominant or master control and will maintain the switch S open. With the construction shown the head pressure must recede about thirty-five pounds before the bellows B₃ will allow the lever 54 to rock back from the position shown in Figure 3 to the position shown in Figures 1 and 2, and restore the control to the bellows B₁ and B₂.

Various types of means may be employed for adjusting the tension of the springs 35, 36, and 61. The springs 36 and 61 are shown as adjustable from adjusting screws 65 and 66, respectively. The heads of these screws are disposed above the top of the casing and their threaded shanks extend vertically down and cooperate with nuts 67 and 68 permanently or fixedly attached to the upper convolutions of their respective springs. A plate-like key 70 is combined with the nut 67 and has sliding contact with the adjacent side wall of the housing 1 to overcome any tendency of the nut or spring to turn. This expedient is not necessary with the spring 61 since it is a lighter spring and can be manually held when its screw is adjusted. The spring 35 also has a nut 71 combined with the upper end thereof, the nut 71 having a plate-like key 72 in sliding contact with the adjacent side wall of the housing. The screw 73 by which the spring 35 is adjusted is threadedly engaged with the nut 71 and extends up above the top of the housing 1. A collar 75 is fixed to the end of the screw projecting above the top of the main housing 1 and is formed with a series of radial slots 76 extending outwardly through its periphery. A knob 77 is placed above the collar with its hub surrounding and in spaced relation to the upper end of the screw 73. The knob 77 has a depending driving lug 78 selectively engageable in the slots 76 and projecting down below the collar so as to be cooperable with a stop lug 79 projecting up from the main housing. An internally threaded sleeve screw 80 is inserted in the hub of the knob 77 and is threaded on the upper end of the adjusting screw 76 above the knob. The upper end of the sleeve screw 80 is formed with a flange 80' which has clamping engagement with the knob to hold it in position with its driving lug positioned in the selected slot of the collar. Such a construction allows the user of the device limited adjustment of the cut-out bellows, thereby facilitating frequent and easy changes in the operating temperature.

Obviously the device is susceptible to either pressure or temperature control and is not limited to use with capillary tube and bulb. Any of the standard temperature elements, such as those adapted for closed tank immersion or for sensitive control immersion, or sensitive control for closed tank, or for air exposure, for pipe wrap exposure, or the like, may be advantageously utilized.

In the construction shown in the drawings, and described hereinabove, the bellows B₁ and B₂ are indicated as being responsive to the same source of pressure. The present invention also contemplates an organization wherein these bellows B₁ and B₂ are responsive to independent sources of pressure or of temperature. This can readily be accomplished by closing the opening 26 and providing an additional fitting similar to the fitting 25 for the chamber containing the

bellows B₁, as well as for the chamber containing the bellows B₂. More specifically, the bellows B₂, which controls the cut-in, might be made responsive to the temperature of the coil to insure complete defrosting, whereas the cut-out bellows B₁ might be made subject or responsive to the temperature of the environment being cooled or the pressure of the refrigerant in the evaporating coil.

While I have shown and described one construction in which the invention may be advantageously embodied, it is to be understood that the construction shown has been selected merely for the purpose of illustration or example, and that various changes in the size, shape, and arrangement of the parts may be made without departing from the spirit of the invention or the scope of the subjoined claims.

I claim:

1. A control device for the compressor motor of a refrigerating system comprising a single pole, single throw electric switch equipped with a permanent magnet to provide for snap action, a spring for biasing the switch to closed position, cut-out and cut-in bellows responsive to the pressure on the low pressure side of the refrigerating system, two sets of levers, one connecting the cut-out bellows to the switch and the other connecting the cut-in bellows thereto, the latter lever set having a yieldable element therein stronger than the switch spring but weaker than the combined force of the switch spring and the permanent magnet, spring means combined with each set of levers to oppose the action of its bellows thereon, and an independent adjustment for each spring means whereby difference between start and stop can be adjusted to cover the entire range.

2. A control device for the compressor motor of a refrigerating system, an electric switch for controlling the operation of the motor, an operator for said switch, cut-out and cut-in bellows subject to the pressure variations on the low side of the system, a lever actuated by the cut-out bellows and interconnected with the switch operator to cause it to open the switch upon a predetermined fall in the pressure on the low side of the system, a second lever actuated by the cut-in bellows, and a leaf or blade spring carried by said second lever and cooperable with said operator to control the closing of the switch upon a predetermined rise in pressure on the low side of the system.

3. A control device for the compressor motor of a refrigerating system comprising a housing, an electric switch therein for controlling the operation of the motor, means responsive to the pressure on the low pressure side of the system for opening and closing said switch and including a cut-out bellows associated with the housing, a lever fulcrumed within the housing, actuated by the cut-out bellows and controlling the opening of the switch, a retractile coil spring having one end connected to said lever, a nut secured to the opposite end of said spring, a screw interthreaded with the nut and supported on the housing for rotation but held against axial movement and having a portion projecting exteriorly of the housing, in combination with a knob fixed to the projecting portion of the screw, and cooperating means between the knob and the housing for limiting the extent to which the knob may be turned.

4. A control device for the compressor motor of a refrigerating system comprising a housing,

an electric switch therein for controlling the operation of the motor, means responsive to the pressure on the low pressure side of the system for opening and closing said switch and including a cut-out bellows associated with the housing, a lever fulcrumed within the housing, actuated by the cut-out bellows and controlling the opening of the switch, a retractile coil spring having one end connected to said lever, a nut secured to the opposite end of said spring, a screw interthreaded with the nut and supported on the housing for rotation but held against axial movement and having a portion projecting exteriorly of the housing, in combination with a collar fixed to the projecting portion of the screw and having a circumferential series of radial slots extending out through the periphery thereof, a knob having a combined locating and stop lug selectively interfitted with said slots, means for securing the knob to the screw with its lug interfitted in a selected slot, and a fixed stop lug on the housing cooperable with the lug on the knob for limiting the extent to which the knob may be turned.

5. A control device for the compressor motor of a refrigerating system comprising an electric switch for controlling the operation of the motor, means responsive to the pressure on the low pressure side of the system for opening and closing said switch and including a rockable switch operator having a laterally projecting driving pin, a cut-in bellows, a bellows lever actuated by the cut-in bellows, an adjustable spring combined with the lever and opposing the action of the bellows, a switch control lever pivotally supported on and having a one way driving connection with said bellows lever, and a lever spring fixed to the switch control lever and engageable with the driving pin of the rockable switch operator normally to control the closing of the switch under the influence of the cut-in bellows.

6. A control device for the compressor motor of a refrigerating system comprising an electric switch for controlling the operation of the motor, means responsive to the pressure on the low pressure side of the system for opening and closing said switch and including a rockable switch operator having a laterally projecting driving pin, a cut-in bellows, a bellows lever actuated by the cut-in bellows, an adjustable spring combined with the lever and opposing the action of the bellows, a switch control lever pivotally supported on and having a one way driving connection with said bellows lever, a leaf spring fixed to the switch control lever and engageable with the driving pin of the rockable switch operator normally to control the closing of the switch under the influence of the cut-in bellows, a high pressure bellows responsive to condensing pressures, a lever actuated by said high pressure bellows, an adjustable spring combined with said last named lever and opposing the action of said high pressure bellows, said last named lever having an arm provided with a camming portion cooperable with the switch control lever to shift it relative to its bellows lever and bring it into engagement with the driving pin of the switch operator to open the switch upon the occurrence of excessive head pressures and hold it open until the head pressure recedes to a predetermined value.

7. A control device for the compressor motor of a refrigerating system comprising an electric switch for controlling the operation of the mo-

tor, pressure-responsive means operatively interconnected with the switch to open it upon a predetermined drop in pressure but being ineffective to apply a force thereto to cause it to close, and pressure-responsive means operatively interconnected with the switch to provide for its closing upon a predetermined rise in pressure but being ineffective to control the opening of the switch.

10. 8. A control device for the compressor motor of a refrigerating system comprising an electric switch for controlling the operation of the motor, an adjustable pressure-responsive means, a one-way motion transmission train between said means and, said switch effective to open the switch upon a predetermined drop in pressure but being ineffective to apply force to the switch upon a rise in pressure, an independently adjustable pressure-responsive means, and a motor transmission train between said last mentioned pressure responsive means and said switch providing for closing of said switch upon a predetermined rise in pressure but being ineffective to control the opening of the switch.

25. 9. A control device for the compressor motor of a refrigerating system comprising an electric switch for controlling the operation of the motor, a cut-out bellows and spring arrangement operatively interconnected with the switch and normally acting as the sole means to control the opening of the same upon a predetermined drop in pressure, and a cut-in bellows and spring arrangement also operatively interconnected with the switch and acting to control the closing of the switch upon a predetermined rise in pressure but being ineffective in respect of the opening of the switch.

30. 10. A control device for the compressor motor of a refrigerating system comprising an electric switch for controlling the operation of the motor, a cut-out bellows combined with the switch to open the same upon a predetermined drop in pressure but ineffective to close the same, a cut-in bellows combined with the switch to provide for closing of the same upon a predetermined rise in pressure but ineffective to control the opening of the switch, and separate and independent adjustable means for individually regulating the action of each of said bellows.

35. 11. A control device for the compressor motor of a refrigerating system comprising an electric switch for controlling the operation of the motor, means for biasing the switch to closed position, a cut-out bellows operatively interconnected with the switch to open the same upon a predetermined drop in pressure but being ineffective to close the same, a cut-in bellows combined with the switch to control the closing of the same under the influence of its biasing means upon a predetermined rise in pressure but being ineffective to control the opening of the switch, and a separate adjustment for each bellows whereby independent regulation is had over the action of the two bellows so that a difference between start and stop can be adjusted to cover the entire range.

40. 12. A control device for the compressor motor of a refrigerating system comprising an electric switch for controlling the operation of the motor, cut-out and cut-in bellows responsive to the pressure on the low side of the refrigerating system, two sets of levers, one set of levers operatively connecting the cut-out bellows to the switch to cause the switch to open upon a predetermined drop in pressure, but being ineffec-

tive to close the same, the other set of levers operatively connecting the cut-in bellows to the switch to provide for closing of the switch upon a predetermined rise in pressure but being ineffective to control the opening of the same, spring means combined with each set of levers to oppose the action of its bellows thereon, and an independent adjustment for each spring means whereby difference between start and stop can be adjusted to cover the entire range.

13. A control device for the compressor motor of a refrigerating system comprising an electric switch for controlling the operation of the motor, an operator for the switch, a cut-out bellows and spring arrangement, a lever actuated by the cut-out bellows and spring arrangement and having a one-way driving connection with the switch operator to cause it to open the switch upon a predetermined fall of pressure but rendering the lever ineffective to apply force to the switch upon a rise in pressure, a cut-in bellows and spring arrangement, a second lever actuated by the cut-in bellows and spring arrangement, and a driving connection between said second lever and said switch operator to provide for closing of the switch upon a predetermined rise in pressure but rendering the second lever ineffective to control the opening of the switch, and independent adjustments for said spring arrangements.

14. A control device for the compressor motor of a refrigerating system comprising an electric switch for controlling the operation of the motor, a rockable operator for the switch having laterally projecting driving pins, a cut-out bellows and spring arrangement, a lever actuated by the cut-out bellows and spring arrangement and engageable with one of said driving pins to effect opening of the switch upon a predetermined drop in pressure, a cut-in bellows and spring arrangement, a second lever actuated by the cut-in bellows and spring arrangement, and a yieldable connection between said second lever and the other of said pins effective to control the closing of the switch upon a predetermined rise in

pressure but ineffective in respect of the opening of the switch.

15. A control device for the compressor motor of a refrigerating system comprising an electric switch for controlling the operation of the motor, an operator for the switch, a cut-out bellows and spring arrangement, a lever actuated by the cut-out bellows and spring arrangement and having a one-way driving connection with the switch operator to cause it to open the switch upon a predetermined drop in pressure but ineffective to cause the switch to close, a cut-in bellows and spring arrangement, a second lever actuated by the cut-in bellows and spring arrangement, a yieldable connection between the second lever and the switch operator to control the closing of the switch on a predetermined rise in pressure, and means responsive to the head pressure on the high pressure side of said system and cooperable with said second lever to open said switch upon the occurrence of excessive head pressure and to hold it open until the head pressure recedes to a predetermined value, said yieldable connection yielding upon functioning of said last mentioned means.

16. A control device for the pressure motor of a refrigerating system comprising an electric switch, means for opening and closing said switch including a first pressure responsive means, motion transmission means interconnecting said first pressure responsive means and said switch and effective to open the switch in response to a predetermined fall in pressure but ineffective to move the switch upon a rise in pressure, a second pressure responsive means, and a second motion transmission means interconnecting said second pressure responsive means and said switch and effective to close the switch upon a predetermined rise in pressure, but ineffective to open the switch upon a fall in pressure, and means establishing fluid pressure communication between said first and second pressure responsive means.

GEORGE KNAAK.
